HANS KREIDEL, OF WIESBADEN, GERMANY

LUBRICANT COMPRESSOR

Application filed January 12, 1928, Serial No. 246,127, and in Germany December 9, 1927.

In the known high pressure lubricant compressors actuated by hand the filling of the supply container, particularly with consistent grease, is very unsatisfactory. The filling has hitherto always been effected by means of a trowel or by means of a separate filling device. The result of this is that the filling can never be of the required uniform density. The mass of grease with which the device is filled is always liable to contain hollow spaces more or less filled with air. The operation of filling is also tedious and the hands and clothes are frequently soiled whilst doing this. The hollow spaces filled with air and distributed throughout the lubricant in the supply container lead constantly to disturbances in operation of the lubricant compressor. According to the present invention the lubricant is drawn directly into the supply container through the operating cylinder by means of the follower piston due, to the suction action produced by the latter. For this purpose the nozzle together with the non-return valve are made suitably detachable so that the operating cylinder or its extension can be used as a free suction passage. The compressor nozzle is therefore preferably constructed in such a manner, different from the known constructions, that it forms a unit with the non-return valve which hitherto formed an accessory of the operating cylinder. It is loosely fitted, screwed or detachably secured in any other manner to the front portion of the lubricant compressor which forms the extension of the operating cylinder, and is preferably protected against loss and damage by a protecting cap which is screwed over it.

By reason of this construction of the lubricant compressor the filling of the supply container can be effected rapidly, conveniently and uniformly whilst avoiding the use of any auxiliary device. The lubricant can be withdrawn completely and without the formation of hollow spaces from any suitable container by means of the follower piston.

An example of construction according to the invention is illustrated in the accompanying drawing, wherein:

Figure 1 shows a longitudinal section of a

complete high pressure lubricant compressor with a detachable nozzle together with the return valve and the protecting cap screwed thereon.

Figure 2 is an elevation of the nozzle with the rearward extension serving as a fitting member and containing the non-return valve, and

Figure 3 is a sectional elevation, of the lubricant compressor itself ready for filling and after removal of the nozzle.

In these drawings *a* indicates the supply container with follower piston *b* and a removable cover *c* provided with a small air inlet opening. For removing the follower piston from the supply container this is provided with a thin cord *d* or chain which, when the lubricant compressor is ready for operation, is placed into the space between the follower piston and the closing cover *c*. In the opposite end of the supply container *a* there is screwed the closing member *e* which serves as a guide and stop for the operating cylinder *f*. The piston *g* is secured to a bar *h* or into a disc provided with openings for the passage of the lubricant. The spring *i* forms the return spring for the operating cylinder *f* and in this case is provided in the front portion of the supply container *a*. It serves at the same time to press the bar *h*, supporting the piston, against a shoulder of the supply container. The nozzle *k* is provided with a rearward tubular shaft *l*, slidably engaging with the operating cylinder *f* or the extension thereof, which shaft simultaneously forms the valve body for the non-return valve *m*. This tubular shaft *l* of the nozzle *k*, instead of being loosely fitted into position may also be screwed into the operating cylinder or secured thereto, so as to be readily detachable, in any other suitable manner. In order to fit the spring *n* which presses the non-return valve *m* against its seat, into the tubular shaft *l* the shaft *l* is preferably open at the front and screwed to the actual nozzle *k*. A cap *o* screwed upon the closing member *e* of the supply container *a* prevents the nozzle *k*, which by means of the tubular shaft *l* is only loosely held in the operating cylinder *f*, from falling out and being lost when the lubricant

10 15 20 25 30 35 40 45 50 55 60 65 70 75 80 85 90 95 100

compressor is not in use. At the same time it protects the nozzle and also all the parts of the supply container projecting beyond the closing member *e* from damage. For the purpose of filling the supply container *a* the nozzle *k*, together with its tubular shaft *l* and the non-return valve *m* mounted in the latter, are removed from the operating cylinder *f*, after removal of the protecting cap *o*, so that a free passage is formed in the operating cylinder. The free end of the operating cylinder is then inserted into the supply of lubricant and the follower piston *b* is drawn back by means of the cord *d*. By reason of the vacuum thus formed in the supply container *a* the lubricant flows through the operating cylinder *f* and past the pressure piston *g* into the rear portion of the supply container. The front portion of the latter, in which the return spring *i* is located, is not emptied as the pressing up of the follower piston *b* is limited by the bar *h* and therefore does not require refilling. After the supply container *a* has been refilled, the nozzle *k* with its tubular shaft *l* is again secured to the operating cylinder *f* and the lubricant compressor is again ready for operation.

Having now particularly described and ascertained the nature of my said invention, and in what manner the same is to be performed, I declare that what I claim is:

1. In a high pressure lubricant compressor of the class described, a barrel, a high pressure cylinder communicating therewith, a piston for said high pressure cylinder, a discharge nozzle for establishing a lubricant-tight connection between said high pressure cylinder and a part to be lubricated, a conduit member slidably engaging said high pressure cylinder, said member carrying said nozzle and containing a non-return check valve, said member being removable from said high pressure cylinder for filling said compressor therethrough, and a manually retractable piston in said barrel for sucking lubricant into said barrel through said high pressure cylinder when the discharge end thereof is placed in a container of lubricant.

2. A high pressure lubricant compressor comprising, in combination, a barrel, a high pressure cylinder communicating therewith and supplied therefrom, a piston for said high pressure cylinder, a nozzle for establishing a sealed connection between said high pressure cylinder and a part to be lubricated, a check valve assembly interposed between said nozzle and said cylinder, said nozzle and check valve assembly slidably and removably engaging said cylinder whereby said nozzle and assembly may be readily removed as a unit to facilitate filling said compressor through the high pressure cylinder, a piston in said barrel, and manual means for retracting said last named piston

to suck lubricant into said barrel and thereby fill the same.

3. In a high pressure lubricant compressor of the class described, a barrel, a high pressure cylinder projecting from one end of said barrel and reciprocable relative thereto, a piston for said high pressure cylinder, a conduit member detachably carried by said high pressure cylinder and removable for filling said compressor through said cylinder, a sealing nozzle and a ball check valve secured within said conduit member, and a manually retractable piston in said barrel and making a lubricant and air-tight seal therein when moved in both directions for sucking lubricant thereinto through said high pressure cylinder when said nozzle and conduit member are removed therefrom.

4. In a high pressure lubricant compressor of the class described, a barrel, a high pressure cylinder in axial alignment and communicating therewith, a piston for said high pressure cylinder, a discharge nozzle for establishing a lubricant tight connection between said high pressure cylinder and a part to be lubricated, a conduit member slidably engaging said high pressure cylinder, said member carrying said nozzle and containing a non-return check valve, said member being removable from said high pressure cylinder for filling said compressor therethrough, and a manually retractable piston in said barrel for sucking lubricant into said barrel through said high pressure cylinder when the discharge end thereof is placed in a container of lubricant.

5. A high pressure lubricant compressor comprising in combination a barrel, a high pressure cylinder communicating therewith and supplied therefrom, a piston for said high pressure cylinder, a nozzle for establishing a sealed connection between said high pressure cylinder and a part to be lubricated, a check valve assembly interposed between said nozzle and said cylinder, said nozzle and said check valve assembly slidably and removably engaging said cylinder, whereby said nozzle and assembly may be removed as a unit to facilitate filling said compressor through said high pressure cylinder, a piston in said barrel, and manual means for retracting said last named piston to suck lubricant into said barrel, the barrel, the high pressure cylinder and the nozzle all being in axial alignment.

In testimony whereof, I have signed my name to this specification Frankfort-on-the-Main this 22d day of December, 1927.

HANS KREIDEL.
